Application June 3, 1958, Serial No. 51,177

Term of patent 14 years

(Cl. D9—2)

Fig. 1 is a perspective view of a portable electric polishing machine showing our new design;

Fig. 2 is a front view in elevation of the article shown in Fig. 1;

Fig. 3 is a bottom plan view of the article shown in Fig. 1;

Fig. 4 is a top plan view of the article shown in Fig. 1;

Fig. 5 is a side view in elevation of the article shown in Fig. 1; and

Fig. 6 is a rear view in elevation of the article shown in Fig. 1.

The polishing member is omitted in Figs. 2, 3 and 6 for convenience of illustration only. In Fig. 5 the cord

is shown broken away in part to indicate indeterminate length, and this cord is omitted in Figs. 1-4 and 6 for convenience of illustration only. The dominant features of our design reside in the portions shown in full lines.

We claim:

The ornamental design for a portable electric polishing machine, as shown and described.
